UNITED STATES PATENT OFFICE.

WILLIAM K. KIGHT, OF POPLAR BLUFF, MISSOURI, ASSIGNOR OF ONE-HALF
TO HORACE D. WILLIAMS, OF SAME PLACE.

CAR-COUPLING.

SPECIFICATION forming part of Letters Patent No. 627,194, dated June 20, 1899.

Application filed September 9, 1898. Serial No. 690,548. (No model.)

To all whom it may concern:

Be it known that I, WILLIAM K. KIGHT, a citizen of the United States, residing at the city of Poplar Bluff, county of Butler, State 5 of Missouri, have invented a certain new and useful Improvement in Car-Couplers, of which the following is a full, clear, and exact description, such as will enable others skilled in the art to which it appertains to make and use the same, reference being had to the accompanying drawings, forming part of this specification, in which—

Figure 1 is a top plan view of my improved car-coupler. Fig. 2 is a side elevational view 15 of the same. Fig. 3 is a front elevational view. Fig. 4 is a cross-sectional view on line 4 4, Fig. 1. Fig. 5 is a similar view, the parts being shown in a locked position. Fig. 6 is a top plan view of the pin-supporting block, and 20 Fig. 7 is a bottom plan view of the same.

This invention relates to a new and useful improvement in car-couplers of that class commonly known as "link-and-pin" couplers, the object being to provide a supporting-block for 25 the pin whereby when the pin is raised it is supported in said elevated position and when the link is introduced, so that its inserted end passes the path of said pin, said link will engage the supporting-block and permit the pin 30 to fall and engage the link.

With this object in view the invention consists in the novel construction and arrangement of this supporting-block, whereby the pin is supported in an elevated position when 35 raised to permit the link to be withdrawn, and when the link is inserted said supporting-block will be forced laterally to permit the pin to drop to engage the link. The position of the supporting-block when the link is in 40 engagement with the pin is such that the supporting-block is held a considerable distance to one side, so that it rests against the pin and is not affected by the vibrations of the link.

In the drawings, A indicates the draw-head 45 of an ordinary link-and-pin coupler, which draw-head, as is usual in constructions of this kind, is provided with a bell-shaped mouth or opening to guide the link into its pocket B.

C indicates a vertically-movable pin which 50 is arranged in a suitable opening in the draw-head, said pin when in a lowered position pass-

ing through the link-pocket, so as to engage the link.

D indicates a supporting-block for the pin, which is introduced through a lateral opening in the draw-head and whose function is to support the pin in an elevated position when the pin is raised to permit the link to be withdrawn, and when the link is inserted in the draw-head it will contact with said supporting-block, forcing the same laterally to permit the pin to drop and engage the link. This supporting-block is formed with an inclined face d on its forward end, which terminates at its extreme upper end in a nose d', 65 the under side of the supporting-block D being provided with inclined faces d'' and shoulders d''', which coöperate with correspondingly inclined faces a and corresponding shoulders a', arranged on the bottom wall of 70 the opening in the draw-head. By forming two or more inclined faces or cams, on which the supporting-block rides, I am enabled to effect a movement which obviates any tendency of the block binding should it be struck 75 a hard blow by the link, which would tend to cause it to tilt or cant to one side. The two or more cam-faces under such conditions will enable the block to settle itself to a horizontal position and prevent its displacement. 80

The upper face of the block is provided with a notch d''', in which operates the end of the bolt E, the function of said bolt being to limit the inward and outward movement of said supporting-block when in operation 85 when the pin is raised. The supporting-block will move inwardly on the cam-faces a, its nose d' extending under the pin to support the same. As shown in Fig. 4, when the link F is inserted it first contacts with cam-faces 90 a and forces said block to ride upwardly and outwardly on said cam-faces a until the pin is released and falls by gravity to engage the link. When the link is in the position shown in Fig. 5, the nose d' contacts with the pin, 95 and the supporting-block is thereby sustained in its elevated position, the object of this being to keep the supporting-block away from the link when the cars are coupled, so that the vibrations of the link will not wear said 100 supporting-block so as to affect its proper operation.

I am aware that minor changes in the construction, arrangement, and combination of the several parts of my coupler can be made and substituted for those herein shown and described without in the least departing from the nature and principle of my invention.

Having thus described my invention, what I claim, and desire to secure by Letters Patent, is—

- 10 1. In a car-coupler of the link-and-pin type, the combination with the draw-head formed with a lateral opening and provided with a plurality of parallel cam-faces in said opening, which are of uniform inclination and height, of a supporting-block for the pin, provided with a plurality of corresponding cam-faces, and means for limiting the outward movement of the supporting-block, substantially as described.
- 15 2. In a car-coupler of the link-and-pin type, the combination with the draw-head formed with a lateral opening provided with a plurality of cam-faces a and shoulders a' of uniform inclination and height, of a supporting-block provided with a plurality of cam-faces d'' and shoulders d''' of uniform inclination and depth coöperating with the cam-faces and
- 20
- 25

shoulders of the draw-head, and a bolt or projection E , operating in a notch in the upper face of the supporting-block, substantially as described.

3. In a car-coupler of the link-and-pin type, the combination with the draw-head formed with a lateral opening provided with a plurality of cam-faces and shoulders, of a supporting-block D formed with an inclined upper face and a nose which is adapted to sustain the pin of the coupler in an elevated position when the supporting-block is at the inward limit of its movement, said nose being of such length that, when the link of the coupler is introduced to force the supporting-block away from the pin, and the pin engages the link, said nose will contact with the pin and hold the supporting-block in an elevated position, out of contact with the link, substantially as described.

In testimony whereof I hereunto affix my signature, in the presence of two witnesses, this 5th day of September, 1898.

WILLIAM K. KIGHT.
